DRESS

Marie Gentile De Martino, Newark, N. J., assignor to L. Wohl & Company, Inc., New York, N. Y., a corporation of New York

Application October 14, 1949, Serial No. 5,486

Term of patent 3½ years

(Cl. D3—26)

To all whom it may concern:

Be it known that I, Marie Gentile De Martino, a citizen of the United States of America and a resident of Newark, in the county of Essex and State of New Jersey, have invented a new, original, and ornamental Design for a Dress, of which the following is a specification, reference being had to the accompanying drawing, forming a part thereof, in which

Fig. 1 is a front elevational view of the dress, showing my new design; and

Fig. 2 is a rear elevational view thereof.

I claim:

The ornamental design for a dress, as shown.

MARIE GENTILE DE MARTINO.
